COOLING PANEL

Edward J. Clarkin, Florissant, Mo., assignor to Nooter Corporation, St. Louis, Mo.

Filed Jan. 6, 1971, Ser. No. 104,547

Term of patent 14 years

Int. Cl. D23—99

U.S. Cl. D23—127

FIG. 1

FIG. 2

FIG. 3

FIG. 4

FIG. 5

FIG. 1 is a front elevational view of a cooling panel showing my new design,

FIG. 2 is a side elevational view thereof,

FIG. 3 is a top plan view thereof, which is identical to a bottom plan view thereof,

FIG. 4 is a fragmentary sectional view taken along the line 4—4 of FIG. 1, and

FIG. 5 is a fragmentary sectional view taken along line 5—5 of FIG. 1.

The cooling panel is broken away in FIGS. 1 and 2 to indicate indeterminate length.

I claim:

The ornamental design for a cooling panel, substantially as shown and described.
